UNITED STATES PATENT OFFICE.

PAUL ANDRÉ GUINARD, OF PARIS, FRANCE.

PUMP.

1,409,097.

Specification of Letters Patent.

Patented Mar. 7, 1922.

Application filed October 22, 1920. Serial No. 418,768.

To all whom it may concern:

Be it known that PAUL ANDRÉ GUINARD, a citizen of the Republic of France, and a resident of Paris, 122 Rue de la Boetie, 5 Seine, France, has invented certain new and useful Improvements in Pumps, of which the following is a full, clear, and exact description, such as will enable others skilled in the art to which it appertains to carry out 10 the same.

This invention relates to improvements in rotary pumps of the piston type.

The known pumps of this class are constituted by a cylindrical body or rotor which 15 is rotatable within an outer casing provided with suction and delivery necks. Suitable 20 cavities provided in said rotor contain pistons disposed to cooperate in pairs and rotatable about a shaft eccentrically disposed 25 with reference to the shaft of said rotor. The pump may be actuated either by means 30 of the rotor shaft or the shaft which is eccentrically disposed with reference to the pistons. By reason of this combination, 35 said pistons will move within the sockets thereof during the rotation, and will give 40 rise to capacities or chambers whose volume varies from zero to a maximum and again 45 returns to zero, and these variations in 50 volume are used to effect the suction and 55 delivery of the pump.

In the pump, according to this invention, 55 the various parts thereof have been combined in a novel manner, whence will result 60 a minimum size for the pump, and the members 65 thereof will operate in a rational manner, while the liquid stream is drawn in and delivered with continuous action and 70 without interruption of the same.

40 The following description together with 75 the accompanying drawings shows a constructional form of the pump according to 80 this invention.

Fig. 1 is a longitudinal section.

45 Fig. 2 is a cross section on the line X—X

Fig. 1.

Fig. 3 is a cross section on the line Y—Y

Fig. 1.

50 The outer casing of the pump is shown at 1, and it comprises a suction neck 2 and a 55 delivery neck 3. One of the end portions 4 is integral with said casing and the other 60 end portion 5 is secured thereto by bolts. 65 The rotor of the pump comprises two end 70 portions 6 and 7 connected by four sectors

8, and the spaces between said sectors serve to contain the pistons and actuating devices. The pistons which have a rectangular section are shown at 9, 10 and 11, 12, these being disposed in pairs and connected at the 60 ends thereof, the pistons 9, 10 being connected by a cross piece 13 and the pistons 11, 12 by a cross piece 14, said cross pieces being cut away to give passage to the actuating shaft 16.

65 The rotation of said pistons is effected by a cross-shaped member 15 the four arms whereof are in contact with the inner surfaces of said pistons and are transversely slidable thereon. The rotary movement is 70 transmitted to said cross-shaped member 15 by a shaft 16 upon which it is secured by the key 17, said shaft 16 being actuated from the exterior by any suitable means, for instance, by an electric motor. The rotation 75 of the pistons effects the rotation of the sectors 8 secured to the rotor of the pump.

The shaft 16 is mounted eccentrically and with easy friction within two long sleeves 18, 18 serving as bearings for said shaft, 80 and said sleeves are mounted concentrically with easy friction within the sockets 19 and 20 forming extensions of the end portions 6 and 7 of the rotor of the pump. The left hand bearing 18 is provided with a shoulder 85 21 contacting the end plate 5, and upon the end of said bearing is screwed the oil cap 28. The right hand bearing 18 serves to maintain the packing member 23 which provides for the tight working of the shaft 16 90 and is held in place by the end piece 24. One end of the sleeve 18 may be provided with a lug 29 adapted to extend within the key way slot or groove 30 formed within the end portion 4 of the casing which will retain the 95 sleeve 18 in a stationary position and thereby prevent it from rotating with the shaft 16.

The operation of the device is as follows:

The shaft 16 effects the rotation of the cross-shaped member 15 which actuates the 100 pistons 9, 10 and 11, 12, and these latter actuate the rotor of the pump by their contact with the members 8. In this movement, the pistons rotate about an axis in plane a—a, the rotor about an axis in plane b—b, and 105 in this manner the rotor is given a diametral movement with reference to said pistons, as well as a movement perpendicular to the diameter which is permitted by the sliding of the inner surfaces of said pistons upon the 110

cross-shaped member. If the rotation is supposed to take place in the sense of the arrow F, the piston 9 will take the place of piston 11 and at the end of a half revolution it will 5 take the place of piston 10, while the piston 10 takes the place of piston 12 and finally of piston 9. The corresponding capacity of the outer face of piston 9 is zero in the first place and then reaches a maximum when 10 piston 9 takes the place of piston 10, and this maximum capacity will return to zero when said piston continuing its movement in the sense of the arrow shall return to 9. These variations in volume are used to effect 15 the suction and delivery. It will be observed that the suction and delivery necks are provided on the interior with suitable recesses 25 and 26 for maintaining the desired communication and the pistons.

20 Manifestly, the construction shown is capable of considerable modification and such modification as is within the scope of my claim, I consider within the spirit of my invention.

25 Having now described my said invention and the best means I know for carrying the

same into effect, what I claim as new and desire to secure by Letters Patent is:

desire to secure by Letters Patent. A pump of the character described comprising in combination a casing, a detachable head plate connected to said casing, cylindrical sleeves mounted within said casing and head plate, the adjacent ends of said cylindrical sleeves being retained in spaced relation, a driven shaft journalled eccentrically in said sleeves, a rotor comprising a pair of flanged sleeves journalled upon the adjacent ends of said cylindrical sleeves and arranged concentrically therewith, sector members connecting said flanged sleeves, a slidable piston arranged between each, a pair of adjacent sector members, said pistons being connected in pairs, a cross-shaped member fixed to said driven shaft, the extremities of the arms of said cross-shaped member being arranged in sliding contact with the interior faces of said pistons, and said casing having an inlet and outlet port.

In witness whereof I have hereunto set my hand.

PAUL ANDRÉ GUINARD.
